CLAIM

The ornamental design for an industrial robot, as shown and described.

DESCRIPTION

FIG. 1 is a first perspective view of an industrial robot showing our new design;

FIG. 2 is a second perspective view thereof;

FIG. 3 is a third perspective view thereof;

FIG. 4 is a fourth perspective view thereof;

FIG. 5 is a front view thereof;

FIG. 6 is a rear view thereof;

FIG. 7 is a right side view thereof;

FIG. 8 is a left side view thereof;

FIG. 9 is a top plan thereof; and,

FIG. 10 is a bottom plan view thereof.

The broken line showing of the remainder of the industrial robot represents portions which form no part of the claimed design.

1 Claim, 10 Drawing Sheets
